UNITED STATES PATENT OFFICE.

ALEXANDER WALKER, OF WHAT CHEER, IOWA.

BOXING FOR DRILLS.

1,273,961.

Specification of Letters Patent. Patented July 30, 1918.

Application filed November 7, 1917. Serial No. 200,810.

To all whom it may concern:

Be it known that I, ALEXANDER WALKER, a citizen of the United States, residing at What Cheer, in the county of Keokuk and State of Iowa, have invented certain new and useful Improvements in Boxings for Drills, of which the following is a specification.

This invention relates to boxing for drills and has special reference to the means whereby the sections of the boxing are fastened around and in engagement with the thread bar of the drill. The object of the invention is to provide a simple and efficient device which may be applied to any boxing now in use and which may be very easily operated.

The invention is illustrated in the accompanying drawings and will be hereinafter fully described, the novel features being subsequently particularly pointed out.

In the drawings:

Figure 1 is a perspective view of a side gear boxing having my invention applied thereto;

Fig. 2 is an end view of the same;

Fig. 3 is a section on the line 3—3 of Fig. 2 showing the parts in the locked position;

Fig. 4 is a similar view showing the parts in the released position;

Fig. 5 is a detail perspective view of the locking lever;

Fig. 6 is an end view of an end gear boxing having the invention applied thereto;

Fig. 7 is a section on the line 7—7 of Fig. 6;

Fig. 8 is a plan view of the arrangement illustrated in Fig. 6.

The boxing consists of two substantially semi-cylindrical members 1 and 2 which are internally threaded, as shown at 3, to engage the thread bar of the drill and are hingedly or pivotally connected at one side by a pin or similar device 4. In the form of boxing shown in Figs. 1 to 5, trunnions 5 are provided at one end of the section 2 of the boxing to engage notches in a drill supporting post, and at the opposite end of the boxing, supporting devices 6 for the drill operating gearing are provided.

Upon the lower section 2, at the free edge of the same and preferably midway its ends, I form a fulcrum pin 7 at the base of which is a substantially semi-circular enlargement 8 having its upper edge beveled, as shown at 9, whereby the outer face 10 of the said enlargement will extend slightly above the inner face thereof or the juncture of the

same with the surface of the section 2 of the boxing.

The peripheral edge of the enlargement 8 is provided below the pin 7 with a shoulder 11 which extends longitudinally with respect to the said pin and the upper beveled edge of the enlargement extends in a straight line transversely with respect to the pin and longitudinally with respect to the section 2 of the boxing, as clearly shown in Fig. 3. The section 1 of the boxing is provided with a projection or lug 12, the lower edge 13 of which is beveled to rest upon the beveled edge 9 of the enlargement 8 and this beveled edge also extends transversely with respect to the pin 7 and longitudinally with respect to the section 1 so that an intimate contact between these two beveled faces may be obtained. The lug or projection 12 has its outer peripheral surface flared outwardly from the surface of the section 1 of the boxing, as shown most clearly in Fig. 2, and it will be noted upon reference to said figure 80 that the outer plane faces of the enlargement 8 and the lug or projection 12 are inclined relative to the vertical plane of the boxing. Adjacent the enlargement 8, I loosely mount upon the fulcrum pin 7 a cam or locking lever 14 which has its upper portion shaped to be easily gripped or handled by the operator and has its lower portion in the form of a ring 15 encircling the fulcrum pin and having its inner face 16 inclined to rest against the outer inclined face of the enlargement 8 and the projection 12, the outer face of the ring-like body 15 being disposed at a right angle to the axis of the pin 7 and adapted to bear against a retaining washer 17 which is secured upon the said pin by a retaining pin 18 inserted through the washer and the fulcrum. The operating lever is constructed with a rib 19 projecting from the inclined face 16 and having an eccentric inner surface 20 adapted to ride over the upper peripheral surface of the lug 12 and thereby force the lug against the projection or enlargement 8 so as to positively lock the sections of the boxing together, and it will be readily noted that the rib 19 with its surface 20 overhangs the lug 12 so that as the lever is turned to the locking position shown in Figs. 2 and 3, it will bind between the washer and the outer faces of the lug 12 and enlargement 8 and tend to draw the lug and enlargement longitudinally of the fulcrum 7 as well as force them together across the said fulcrum. The parts will thus be

caused to bind together with sufficient holding force to withstand all ordinary usage and remain closed under accidental blows. Upon reference to Figs. 1 and 3 it will be noted 5 that in order to lock the sections together the miner or other user of the drill will move the upper end of the locking lever toward himself and is, therefore, not required to perform any unnatural or laborious 10 movement in locking the boxing. To release the boxing the upper end of the lever is merely pushed forward, as shown in Fig. 4, and to limit this forward movement a stop shoulder 21 is provided at the end of the rib 15 19 to engage against the shoulder 11 on the enlargement 8 so that the locking lever is not given a very lengthy movement either to lock or unlock the boxing and when in unlocked position it will be supported so that 20 it may be easily and readily reached by the miner and quickly brought to the locking position.

In the form of the invention shown in Figs. 6, 7 and 8, the trunnions 25 are provided generally at points midway the ends 25 of the respective boxing sections 26 and 27 which are hinged together at one side by a pin 28 inserted through coacting lugs or ears formed on the sections at the end of 30 one of the trunnions. The trunnion projecting from the free edge of the lower section 27 is in this instance utilized as the fulcrum for the locking lever 29, an enlargement 30 being formed around the base of 35 said trunnion and having a stop shoulder 31 and an upper beveled or inclined surface 32 corresponding to similar elements in the previously described form. The upper section 26 is provided with a projection 33 40 adapted to project over the enlargement 30 and having an under inclined face 34 adapted to rest upon the inclined face 32 of said enlargement. The locking lever is mounted upon the fulcrum 25 and its outer face is 45 inclined in one direction so as to have a wedging binding action upon the retaining washer 35 which is held upon the trunnion 25 by a fastening pin 36. The lever is provided on its inner face with an overhanging 50 rib 37 having an eccentric inner surface 38 and terminating in a shoulder 39 adapted to bear against the stop shoulder 31. The inner peripheral face of the rib 37 in this 55 form of the invention extends parallel to the longitudinal axis of the trunnion and the upper surface of the lug 33 also extends parallel to said axis, the desired binding action being obtained by the inclined coacting faces of the lever and the washer 35. The 60 manipulation of the lever is the same in every respect as the action of the lever in the previously described form.

In Figs. 1 and 2 is shown a flat-sided lug

40 at the rear end of the section 1 and disposed longitudinally on the upper side thereof. In the use of boxings now on the market, when it is desired to open the boxing a pick or other sharp instrument must be inserted between the free meeting edges of the sections which are then pried apart. In my 70 improved boxing, the lug or projection 40 constitutes a thumb rest and a slight lateral pressure on the same suffices to open the boxing.

Having thus described the invention, what 75 is claimed as new is:

1. The combination of boxing sections provided with coacting projections, a fulcrum projecting from the lower section concentric with the projection thereon, and a locking 80 lever rotatably mounted upon said fulcrum adapted to bear eccentrically upon the projection on the upper boxing section, the locking lever and the projection on the lower boxing section having coacting stop shoulders 85 whereby to limit the releasing movement of the lever.

2. The combination of boxing sections having projections at their free edges provided with coacting inclined faces, a fulcrum projecting from one of the sections, and a locking lever rotatably mounted upon 90 said fulcrum and having an overhanging rim extending partly around the projections on the boxing sections and an eccentric inner face to engage one of said projections and bind them together.

3. The combination of boxing sections, projections on the free edges of said sections adapted to abut when the sections are 100 closed, a fulcrum extending from one of said projections, a locking lever rotatably mounted upon said fulcrum and having its inner face bearing against the projection at the base of the fulcrum and constructed with 105 an overhanging eccentric rib adapted to bind upon the outer surface of the other projection, and means for retaining the locking lever upon the fulcrum.

4. The combination of boxing sections, a 110 fulcrum projecting from one of the sections at the free edge thereof, an enlargement around the base of said fulcrum, a lug on the other boxing section adapted to bear upon said enlargement, a retaining washer 115 secured upon the fulcrum, and a locking lever rotatably fitted upon the fulcrum between said washer and the enlargement at the base of the fulcrum, said lever having an overhanging eccentric rib adapted to bear 120 upon the lug coacting with said enlargement, and one face of said lever being disposed obliquely with respect to the longitudinal axis of the fulcrum.

In testimony whereof I affix my signature, 125
ALEXANDER WALKER. [L.S.]
